(57) **CLAIM**

The ornamental design for an autoinjector with removable cap as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view showing a new design for an autoinjector with a removable cap, showing the removable cap disposed on the autoinjector;

FIG. 2 is a front view of the autoinjector with removable cap of FIG. 1;

FIG. 3 is a rear view of the autoinjector with removable cap of FIG. 1;

FIG. 4 is a left-side view of the autoinjector with removable cap of FIG. 1;

FIG. 5 is a right-side view of the autoinjector with removable cap of FIG. 1;

FIG. 6 is a top view of the autoinjector with removable cap of FIG. 1;

FIG. 7 is a bottom view of the autoinjector with removable cap of FIG. 1; and,

FIG. 8 is a perspective view showing the autoinjector with removable cap of FIGS. 1-7 with the removable cap removed.
